MEASURING CAP FOR A JAR

Harry C. Gessler, Brooklyn, N. Y., assignor to
 Medco Products Co. Inc., North Bergen, N. J.,
 a corporation of New Jersey

Application May 3, 1949, Serial No. 2,397

Term of patent 14 years

(Cl. D58—26)

To all whom it may concern:

Be it known that I, Harry C. Gessler, a citizen of the United States and resident of Brooklyn, in the county of Kings and State of New York, have invented a new, original, and ornamental Design for a Measuring Cap for a Jar, of which the following is a specification, reference being had to the accompanying drawing, forming a part thereof, and of which

Figs. 1 and 2 are, respectively, front and side elevational views of a measuring cap for a jar showing my new design, and

Figs. 3 and 4 are, respectively, top and bottom plan views of the measuring cap for a jar shown in Fig. 1.

I claim:

The ornamental design for a measuring cap for a jar, substantially as shown.

HARRY C. GESSLER.
